UNITED STATES PATENT OFFICE

2,560,532

FLUSH TANK

Parker Cole, San Gabriel, Calif., assignor of one-half to Arthur T. Cole, Alhambra, Calif.

Application June 11, 1949, Serial No. 98,449

4 Claims. (Cl. 4—47)

1

This invention relates to flush tanks and similar liquid discharging devices.

An object of the present invention is to provide control means in a flush tank or the like wherein the conventional ball valve is eliminated and wherein the water is siphoned out of the tank rather than merely dumped as when a valve is employed.

Another object of the invention is to minimize the noise usually attending the operation of conventional flush tanks by instituting a quietly operating siphon action to effect discharge of water in the tank.

Another object of the invention is to insure discharge of a required amount of water from the tank and to obviate premature shut-off as may occur when a valve control is used.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a front elevational view, partly in vertical section, showing a flush tank embodying a structure according to the present invention.

Fig. 2 is a plan sectional view as taken on line 2—2 of Fig. 1.

The flush tank 5 is of conventional form and includes a standard discharge fitting 6 and a standard inlet fitting 7, both carried by the bottom wall 8 of the tank. Also, conventionally, a loosely fitting cover 9 is applied to the top of the tank. Fitting 7 mounts a ball cock valve 10 that controls inlet of water and the latter has a filler tube 11 extending therefrom and into fitting 6.

According to the present invention an extensible siphon 12 is disposed in tank 5 and carried by fitting 6, a float 13 is connected to the siphon to extend the same when buoyed up by water in the tank, and manual means 14 is provided for contracting the siphon to institute a flushing operation.

The siphon 12 comprises a stand pipe 15 extending from fitting 6, a siphon discharge leg 16

2

loosely telescoped in pipe 15, a siphon inlet leg 17 arranged in parallel relation to leg 16, and a preferably smooth 180° bend 18 connecting the upper portions of the siphon legs.

5 Actually, the siphon discharge leg comprises leg 16, that portion of pipe 15 which extends therebelow, the fitting 6, and such tube or pipe (not shown) that extends from said fitting for connection to a receptacle receiving the discharge from the tank. Inlet leg 17 is shorter than the leg just described and terminates at the bottom in a laterally angularly directed inlet opening 19.

To prevent fluid leakage into the extensible leg of the siphon, a suitable seal 20 is provided to seal between pipe 15 and leg 16. When, as shown, leg 16 is inside pipe 15, said seal is disposed between the upper end of said pipe and the upper end of the leg immediately below the start of bend 18. Tube 16 may externally engage pipe 15, in which case seal 20 would be placed adjacent fitting 6. In either case, seal 20 may comprise the extensible bellows shown or other suitable sealing devices.

The float 13 is affixed to the siphon. The size 25 of the float and its position relative to that point 21, the lowest point of bend 18, is such that when it is floated or buoyed by water, said point 21 will not be immersed. The level of water 22 must be below point 21 when the siphon is extended due to the buoyancy of the float. This is the initial level of water before flushing is instituted. The form of float is immaterial, but the siphon bend 18 is to be connected thereto whereby the point 21 will be above the bottom of the float a sufficient distance to also be above the level of the water in which the float is buoyed.

The means 14 comprises an operating handle 23, preferably pivoted, and an arm 24 extending from the handle pivot and engaged with the top of float 13.

Operation

Handle 23 is depressed, causing arm 24 to press 45 against float 13 to cause depression of the extended portion of the siphon-legs 16 and 17 and bend 18. Seal 20 will collapse accordingly. As point 21 is submerged below water level 22, water in leg 17 will spill thereover into leg 16. As the 50 float is further depressed to the dot-dash position, the water will fill bend 18 to the exclusion of air and the siphon is started, the water being drawn through inlet 19 and discharging through fitting 6. Water level 22 will lower as the discharge progresses until the topmost por-

tion of said inlet 19 is uncovered and the siphon is broken. The depleted level will then be at 25. The siphoning force will draw all the water out of leg 17 leaving only the residue of water to the level of 25. As the tank is again filled through inlet 7 and ball cock valve 10, the siphon will retain its depressed or low position until the float 13 is again buoyed up and, when the level 22 is achieved, the inlet flow will stop and the tank is again ready to be operated.

The ball cock valve 10, through an arm 26 that straddles leg 17 and a connecting rod 27, is controlled by the float, being closed when the float is up and open when said float is depressed.

While the invention that has been illustrated and described is now regarded as the preferred embodiment, the construction is, of course, subject to modifications without departing from the spirit and scope of the invention. It is therefore not desired to restrict the invention to the particular form of construction illustrated and described, but to cover all modifications that may fall within the scope of the appended claims.

Having thus described my invention, what I claim and desire to secure by Letters Patent is:

1. In a flush tank, an extensible siphon comprising a stand pipe terminating in a bottom discharge, a siphon discharge leg telescopically engaged with said stand pipe, a siphon inlet leg, a bend connecting the upper ends of said legs, means connecting the stand pipe and discharge leg to seal between the same, a float carried by said legs and bend to buoyantly hold the bend above the level of water in the tank, and manual means to depress the float and thereby telescopically slide the discharge leg relative to the stand pipe to contract the siphon and depress said bend

below said water level for starting siphoning of the water in the tank.

2. A siphon for a flush tank and the like comprising a longer extensible discharge leg, a shorter inlet leg, a 180° bend connecting said legs, and a float connected to said bend and having buoyancy to extend the extensible leg.

3. A siphon for a flush tank and the like comprising an extensible discharge leg, an inlet leg generally parallel to the discharge leg, a bend connecting the upper ends of said legs, and a float connected to said bend and having buoyancy to extend the discharge leg.

4. A siphon for a flush tank and the like comprising an extensible discharge leg, an inlet leg generally parallel to the discharge leg, a bend connecting the upper ends of said legs, and a float mounted directly on the bend and having buoyancy to simultaneously elevate the inlet leg and extend the discharge leg.
